UNITED STATES PATENT OFFICE

FRANK B. SECOR, OF NEWARK, NEW JERSEY, ASSIGNOR TO KERLOW STEEL FLOOR COMPANY, OF JERSEY CITY, NEW JERSEY, A CORPORATION OF NEW JERSEY

FLOOR GRATING

Application filed April 26, 1929. Serial No. 358,244.

This invention relates to steel floor gratings of the type which is made up in units of longitudinally disposed bars or girders separated and secured together by spacing members.

5 Among the objects of this invention is to produce a floor grating of a design which will possess the requisite amount of strength and yet be so characterized by its simplicity of construction as to render it capable of being manufactured at low cost.

Another object of the invention is to provide a design of floor grating requiring but one working operation to unite one girder or 15 bar with two spacing members.

Another object of the invention is to provide a grating which may be almost entirely assembled by hand operation and without the use of tools.

20 Another object of the invention is to provide a grating having the appearance of a multiplicity of crossed rods, of which the rods in one direction are assembled from a number of spacing members which are connected in series and form lateral rows of connected spacing members.

The principle embodied in my invention includes the use of girders of any usual type, such as straight bars, and spacing members 30 designed so that a spacing member engages two girders and also engages the spacing members on the other sides of the two engaged girders. The form of grating herein illustrated includes straight bars and spacing members, each spacing member consisting of a short bar having a tread length equal to the desired lateral spacing of the longitudinal girders and having a projection and a hole for enabling engagement of successive 35 spacing members. While force fits may be used, a screw connection has advantages and I therefore thread the projection and tap the hole of each spacing member. Successive spacing members are screwed together after 40 the projection of a connecting spacing member has been passed through a hole in a girder. The grating is built up by putting together alternately longitudinal rows of spacing members and girders.

50 The details of this invention are illustrated

in the accompanying sheet of drawings in which:—

Fig. 1 is a plan of a simplified form of a unit of a floor grating.

Fig. 2 is a section on line 2—2 of Fig. 1.

55

Fig. 3 is a perspective view of a girder.

Figs. 4 and 5 are perspective views of suitable spacing members.

Fig. 6 illustrates a spacing member made of two pieces.

60

As is customary in floor gratings a number of girders or bars 10 and spacing members 11 are assembled together in a unit of specified dimensions which depend upon convenience, intended use and strength of the elements used in the construction.

As is customary in floor gratings a number of girders or bars 10 and spacing members 11 are assembled together in a unit of specified dimensions which depend upon convenience, intended use and strength of the elements used in the construction.

In the present form of the invention straight bars constitute the girders and since these are designed so as to be able to carry all of the vertical load they are so positioned that their narrow dimensions may rest upon supporting structure, not shown. The girders run lengthwise of the grating and are generally spaced laterally from each other and parallel to each other.

70

The spacing members 11 serve primarily to maintain the girders of a unit in definite relation to each other and their uppermost surfaces or projections lie in the same plane as the upper edges of the girders 10 so as to define the walking surface of the floor grating and at the same time prevent slipping in a direction lengthwise of the grating. In addition, the present type of spacing members contributes materially to the transverse strength of the floor grating.

80

Each spacing member 11 is of a very simple form and can be made from an ordinary stock rod cut up into suitable lengths. For example, the different styles of spacing members illustrated in Figs. 1, 4 and 5 may be made by cutting a bar, a smooth or a deformed bar as the case may be, into over-all lengths including the length of the tread portion and projection 12. One end of the member so obtained is then turned down until the projection 12 assumes the desired diameter for threading and the uncut portion is of such length as is desired for the spacing of the girders 10 of the grating. The pro-

90

95

100

jection 12 is then threaded and a hole 13 is drilled and tapped at the other end of the spacing member.

The design of the surface of the spacing member is largely a matter of choice and consideration might be given to the particular manner in which the grating is to be used, that is, as a ventilated flooring or as a foundation for a concrete and steel flooring.

10 An alternate form of spacing member is illustrated in Fig. 6. This spacing member may be constructed by drilling a hole 14 throughout the length of spacing member. The hole is then tapped and a stud 15 is 15 screwed into the hole. The length of the stud should preferably not exceed the length of the tread portion of the spacing member. A portion of the stud remains extending so as to enable connection with another spacing 20 member in the manner which will now be described.

In assembling a grating involving the principle of my invention a workman would start by selecting a number of girders of the 25 required weight and length and which had previously been punched with holes 16 large enough to accommodate the threaded projection of a spacing member 11. These holes, Fig. 3, would have been so placed as to position the upper surface of the tread portion 30 of the spacing member in the same plane, or approximately so, with the upper or floor surface of the grating. Each of the spacing members 11 for the grating to be constructed 35 is individually attached to a girder by suitable means 17 which may be in the form of a screw or a force fitting member such as a drive rivet. Each spacing member 11 of the first longitudinal row of spacing members is 40 connected to the first girder 10, Fig. 1, in this manner. After each spacing member of the first longitudinal row of spacing members has been affixed to the first girder a second girder is placed in position with the 45 series of threaded projections 12 extending through its series of holes 16. Thereafter a second longitudinal row of spacing members placed in position as each one of the longitudinal row is made to engage with the preceding spacing member in its lateral row. The engagement of one spacing member with 50 another is obtained by turning the newly added member as its tapped hole 13 is engaged by the threaded projection 12 of the spacing member already in place. It would probably be desirable to use a pipe wrench for screwing the members into a tight engagement, but in gratings in which a real tight 55 connection could be dispensed with a work- 60 man would not have to use any greater effort than that obtainable by the use of his hands and without the assistance of any tool. It will be appreciated that after a grating is 65 made up, individual spacing members may not become loosened since the remaining

spacing members in the same longitudinal row would maintain the relatively stiff girders at a fixed distance apart.

The width of a grating may be built upon by adding successively longitudinal rows of spacing members and girders until the desired width is obtained. Each spacing member in the last longitudinal row of spacing members should be preferably of the kind illustrated in Fig. 6 without a stud so that a drive rivet or screw may be driven home in each of such spacing members after the last girder is in place, Fig. 1.

I claim:

1. A grating comprising spaced longitudinal girders and assembled bars disposed transverse to said longitudinal girders, each assembled transverse bar comprising a row of aligned spacing members bracing the spaced longitudinal girders laterally, there being a projection from one spacing member passing through an opening of a contiguous longitudinal girder and into engagement with a hole in an associated spacing member on the other side of the contiguous longitudinal girder. 80

2. The combination set forth in claim 1 in which the projections of the spacing members are threaded and the holes in the spacing members are tapped. 95

3. The combination set forth in claim 1 in which each spacing member has a tapped hole throughout its length and a stud extending from one end of the tapped hole constitutes a threaded projection. 100

4. A floor grating comprising spaced bars and parallel rows of spacing members, each spacing member having a hole at one end and a projection at its other end whereby a row of spacing members comprises aligned spacing members having the projections of successive spacing members passing through holes in the bars and into the holes at the ends of the next succeeding spacing members. 105

5. A grating comprising a series of parallel girders laterally spaced from each other and a plurality of spacing members extending laterally to the girders and between the girders, the spacing members being arranged in rows with each spacing member having a 110 threaded portion extending through a hole in a bar and engaging a tapped hole in the spacing member on the other side of the bar. 115

6. A grating comprising parallel spaced girders and interposed spacing members comprising lengths of bars, each length having a tapped hole at one end and a threaded projection at its other end, the spacing members being so disposed that the threaded projection of one spacing member extends through a hole in a girder and into engagement with the tapped hole of another spacing member. 120

7. A grating comprising a plurality of longitudinal girders and members laterally spacing the girders from each other, there 125 130

being a plurality of lateral rows of spacing members with the successive spacing members of each lateral row connected together, each of said spacing members engaging with a contiguous girder and having a threaded projection engaging a tapped hole in the next succeeding spacing member in the same lateral row.

8. A grating comprising longitudinally extending girders and spacing members therebetween, said spacing members being arranged in rows with successive spacing members of each row connected together by a threaded projection extending from one member and passing through an opening in a contiguous girder and engaging with a tapped hole in the next spacing member in the same row on the other side of the contiguous girder.

20 9. A grating comprising longitudinal girders and spacing members connecting together the girders, there being a plurality of individual spacing members between each pair of girders forming transverse rows of spacing members of which successive spacing members in a transverse row are connected together, each spacing member having at least one shoulder abutting a girder and a surface contiguous with the surface of another girder 25 whereby the girders are maintained in spaced relation, and each spacing member being provided with a threaded projection passing through a hole in one girder and engaging a tapped hole in a spacing member on the other 30 side of the girder having the hole therein and a tapped hole for receiving and engaging the threaded projection of the spacing member on the other side of another girder.

35 In testimony whereof I hereto affix my
40 signature.

FRANK B. SECOR.
